CLAIM

The ornamental design for a display screen with graphical user interface, as shown and described.

DESCRIPTION

FIG. 1 is a front view of a display screen with graphical user interface showing our new design.

FIG. 2 is a front view of the display screen with graphical user interface of FIG. 1 shown on a non-claimed mobile device; and,

FIG. 3 is a front perspective view thereof.

The uneven-length broken lines illustrate a non-claimed boundary of the display screen with graphical user interface. The outermost even-length broken lines illustrate a mobile device, which is the environment of the design, and form no part of the claim. The remaining broken lines illustrate portions of the graphical user interface that form no part of the claimed design.
